UNITED STATES PATENT OFFICE.

EDWARD GLOVER ATKINS, OF MINNEAPOLIS, MINNESOTA, ASSIGNOR TO ATKINS MANUFACTURING COMPANY, OF MINNEAPOLIS, MINNESOTA, A CORPORATION.

CARBURETER OR MIXER FOR INTERNAL-COMBUSTION ENGINES.

1,036,536.

Specification of Letters Patent. Patented Aug. 27, 1912.

Application filed July 8, 1909. Serial No. 506,478.

To all whom it may concern:

Be it known that I, EDWARD GLOVER ATKINS, a subject of the King of Great Britain, residing at and whose post-office address 5 is No. 1025 Third avenue south, Minneapolis, Hennepin county, Minnesota, have invented a new and Improved Carbureter or Mixer for Internal-Combustion Engines, of which the following is a full, clear, and ex- 10 act description.

My invention has for its object to provide an improved carbureter or mixing-valve for internal combustion engines and to this end it consists of the novel devices and combina- 15 tions of devices hereinafter described.

In this improved carbureter no liquid hydro-carbon is allowed to escape into the carbureter to form a puddle or to run over any vaporizing surface, but the parts are so ar- 20 ranged and the size of the oil port so regu- 25 lated that the oil of hydro-carbon is instantly vaporized as it leaves said oil port, and the oil port is automatically closed by the stop- ping of the engine. The oil and air feed 30 automatically in proportion to the speed of the engine under all the varying conditions encountered by boats and automobiles as well as stationary engines. Further a de- 35 vice is provided by means of which the en- gineer may change the adjustment from the usual place of control of the engine such as the steering wheel of an automobile, and this can be readily done even though the automobile is in rapid motion.

35 The improved carbureter is illustrated in the accompanying drawings forming a part of this specification wherein like numerals and characters indicate like parts through- 40 out the several views.

40 Referring to the drawings:—Figure 1, is a vertical section taken centrally through the improved carbureter. Fig. 2, is a plan of the bottom of the carbureter. Fig. 3, is a horizontal section taken through the throttle-piece on the line A—A, Fig. 1. Fig. 4, 45 is a sectional view of the combined oil and air shut-off valves.

The mixing-chamber 1 of the carbureter is within an outer shell or casing 2, the neck 50 3 of which is adapted to be connected, di- 55 rectly or indirectly, with the cylinder of an explosive engine, said neck 3 is the exhaust or outlet from the carbureter for the mixture. In the hollow cylindrical center of the casing 2 a throttle-piece 15^a, 15^b revolves

on a pivot 16 on one end of its axis and on the projection 17^b from the base-piece 28 on the other end. The central portion of said revolving throttle-piece is hollowed out to form the tubular air passage 4 having a contracted neck 5 and shaped at the end 6 so as to be closed by the flange or dia- phragm 10. Both sides of said neck 5 of tubular air passage 4 are cut away imme- diately above the oil port 9, leaving only so 60 much metal as is necessary to form a brace and keep the center rigid. Thus the neck 5 of the tubular air passage is entirely open to the mixing chamber. Two arms of said throttle-piece extend through the center of 70 the base-piece 28 on either side of the oil supply pipe 31 and are fastened to the throt- tle control lever 23 by screws 32.

Extending from the center of the base- 75 piece 28 through and axially of the air pas- sage, 4, is an oil conduit, 8, terminating with a contracted port, 9, said contracted port 9 being located concentrically in the neck 5 of the air passage 4.

A shut-off valve 11 is attached by a guide- 80 piece or sleeve 12 to a diaphragm-valve or flange 10, said guide-piece or sleeve 12 hav- ing ample openings 13 for the passage of the vaporized oil or hydro-carbon. A light spring 33 tends to seat the shut-off valve 85 11, and at the same time close the air entrance 6.

A needle-valve 14 having a screw-threaded stem 18 regulates the contraction of the oil delivery port 9; and the end of the screw- 90 threaded stem passing through the packing- box 24 is fastened to the cog wheel 19. A toothed arm or lever 20 is pivoted on a throttle lever 23 and said toothed arm 20 is 95 pressed into the cogs of the wheel 19 by the spring 21. A wire or cord may be attached to said toothed arm through the hole 22 so that by pulling on the wire will disengage the teeth from the cogs.

An auxiliary air valve 7 is located at a 100 point in the outer shell 2 so situated that air admitted through it must pass by or across the neck 5 of the main air intake pas- sage 4 on its way to the engine cylinder. A spring 25, of greater tension than the spring 33, tends to close said auxiliary air valve 7. A screw 26 serves to adjust the tension of the spring 25 and is locked by the thumb-nut 27.

The oil supply pipe 31 is threaded at the 110

end 29 to connect with a pipe from the tank or reservoir (not shown). The outer portion 15^a of the throttle-piece which revolves in the cylindrical center of the casing 2 is shaped like a one quarter section lengthwise of a closed cylinder having the tubular air passage 4 for its axis and is adapted to open and close the outlet for the mixture through the neck 3. The inside circumference of the cylindrical center of the casing 2 is approximately four times as great as the diameter of the exhaust or outlet passage through the neck 3. Consequently it follows that a one-quarter turn from closed position of the revolving throttle-piece will leave the outer portion thereof 15^a in a position alongside the side wall of the casing. By reason of the arms 15^b striking the gasolene feed pipe 31 it can not turn more than one-quarter around so it can not reach a position which would obstruct the passage of air into the mixing chamber 1 through the auxiliary air valve 7. The closed position of said throttle-piece 15^a can be regulated by the adjustable screw-stop 30. The air passage 4 has openings out of the sides of the neck 5 into the mixing chamber 1.

Special emphasis is laid on the location of the oil port 9 with regard to the air intake valves at 6 and 7. The oil port 9 must be nearer to the engine cylinder along the path traveled by the inrushing air than either of the air entrances, and must also be as nearly in the center of the path traveled by the air from each entrance as possible. Also the unobstructed flow of oil from the reservoir or tank through the supply pipe 31 and oil conduit 8 should continue as close up to the shut-off valve 11 as is consistent with allowing for some wear at this point.

Care must be taken that the diaphragm valve or flange 10 does not seat or strike but should pass freely into the air entrance 6 in the manner of a piston.

When the carbureter is attached to the engine and adjusted thereto and the oil supply connected at 29, its method of operation will be as follows:—On cranking or otherwise starting the engine, the suction of the piston in the engine cylinder creates a partial vacuum in the mixing-chamber 1, and this vacuum immediately causes the diaphragm valve 10 to open and with it the oil shut-off valve 11. At the same instant it causes a quick rush of air through the air passage 4, which, by reason of the shape of the passage and the location of the oil port 9, is deflected across said oil port 9 sucking out and vaporizing all the oil allowed to pass through the contracted port 9. The openings 13 in the guide-piece or sleeve 12 are large enough and so placed as not to interfere with this action. The quantity of oil which can be thus sucked out is limited

and regulated by the action of the needle-valve 14 in the contracted port 9. As the throttle 15^a is turned to open wider the cog-wheel 19 being in mesh with the toothed arm 20, is turned at the same time so as to cause the needle valve 14 to recede from the oil port 9 thus leaving a wider opening for the passage of oil. The wider the throttle is opened the greater suction force is exercised on the air intake valves and an increasing volume of air is drawn in, all of which rushes by the oil port 9, picking up and vaporizing the oil on the way. Closing the throttle reverses the process, that is to say less air and less oil is admitted and the moment the engine stops the shut-off valve 11 and the flanged extension or diaphragm valve 10 are pushed back to their normal position by the spring 33.

If it is desired at any time to change the oil feed, it can be done by disengaging the toothed arm 20 from the cog-wheel 19 and turning the throttle independently either way according to whether an increase or decrease of oil is desired and then allowing the toothed arm 20 to again spring back to engage the cog wheel at a new point of contact.

The shape of parts may be varied so long as the proper relation of the same to each other is maintained; and consequently I do not limit myself to the precise details of construction hereinbefore enumerated.

Having thus described the invention, what I claim and desire to secure by Letters Pat- 100 ent is:—

1. In a carbureter, the combination with a casing or mixing chamber, of a main air intake passage having a contracted neck at the end which opens into said mixing chamber and opening at the other end to the atmosphere, a yieldingly closed auxiliary air intake valve opening into said mixing chamber and arranged to be opened by suction and so placed that the air admitted must pass over or by the open neck of the main air intake passage, an oil supply conduit having a contracted port and unobstructed except at said contracted port, the said contracted oil delivery port being located in the contracted neck of said main air intake passage and well above the open end communicating with the atmosphere, and two valves cooperating with said oil delivery port, the one serving to regulate the contraction of said port, and the other being actuated by suction and serving to open and close the oil port and having a flanged extension which serves to open and close the end of the main air passage simultaneously with the opening and closing of the oil port.

2. In a carbureter, the combination of a throttle piece serving to control the passage of the mixture out of the carbureter, with

a screw-threaded-needle-valve controlling the volume of oil admitted, a separate connecting piece or link between said throttle piece and said screw-threaded-needle-valve 5 causing said needle-valve to turn in like proportion to the throttle, and means for moving said connecting piece or link at a distance from the carbureter so as to change its point of contact on the screw-threaded-needle valve or to disengage it from any contact whatsoever.

3. In a carbureter, the combination with a casing or mixing valve, of a main air intake passage having a contracted neck at 15 the end which opens into said mixing chamber and opening at the other end to the atmosphere, a yieldingly closed auxiliary air intake valve opening into said mixing chamber and arranged to be opened by suction and so placed that the air admitted 20 must pass over or by the open neck of the main air intake passage, an oil supply conduit having a contracted port and unobstructed except at said contracted port, the 25 said contracted oil delivery port being located in the contracted neck of said main air intake passage and well above the open end communicating with the atmosphere, two valves coöperating with said oil delivery 30 port, the one serving to regulate the contraction of said port, and the other being actuated by suction and serving to open and close the said oil port, and having a flanged extension which serves to open and 35 close the end of the main air passage simultaneously with the opening and closing of the oil port, a throttle piece serving to control the outlet of the mixture from the carbureter, a screw-threaded stem on the needle 40 valve serving to regulate the contraction of the oil delivery port, a connection between said screw-threaded-needle-valve and said throttle piece causing said needle valve to turn in like proportion to the throttle, and 45 means for moving said connection at a dis-

tance from the carbureter so as to change its point of contact on the screw-threaded-needle-valve.

4. In a carbureter, the combination, with a casing or mixing chamber, of a main air intake passage having a contracted neck at the end which opens into said mixing chamber and opening at the other end to the atmosphere, a yieldingly closing auxiliary air intake valve opening into said mixing 50 chamber and arranged to be opened by suction and so placed that the air admitted must pass over or by the main air intake passage, an oil supply conduit having a contracted port and unobstructed except at 55 said contracted port, the said contracted oil delivery port being located in the contracted neck of said main air intake passage and well above the open end communicating with the atmosphere, two valves coöperating 60 with said oil delivery port, the one serving to regulate the contraction of said port and the other being actuated by suction and serving to open and close the said oil port and having a flanged extension which serves 65 to open and close the end of the main air passage simultaneously with the opening and closing of the oil port, a throttle piece 70 serving to control the outlet of the mixture from the carbureter, a screw thread on the stem of the needle valve which serves to regulate the contraction of the oil admission port, a cog wheel attached to said screw-threaded-valve-stem, a toothed arm to engage the cogs and connect said throttle 75 piece to said screw-threaded-valve-stem, said toothed arm being normally pressed into position by a spring, substantially as shown and described.

In testimony whereof I have hereunto set 80 my hand in the presence of two witnesses:
